Filed Jan. 11, 1962, Ser. No. 68,276

Term of patent 14 years

(Cl. D62—2)

FIGURE 1 is a side elevational view of a hydro-pneumatic gun embodying our new design, the side opposite being substantially a mirror image thereof.

FIGURE 2 is a rear elevational view of the hydro-pneumatic gun shown in FIGURE 1;

FIGURE 3 is a bottom plan view of the hydro-pneumatic gun of FIGURES 1 and 2; and

FIGURE 4 is a front elevational view of the hydro-pneumatic gun shown in FIGURE 1 drawn to a reduced scale.

We claim:

The ornamental design for a hydro-pneumatic gun or the like, substantially as shown and described.
